WHEEL

Alexander Brede III, East Lansing, Mich., assignor to
Motor Wheel Corporation, Lansing, Mich., a corpora-
tion of Ohio

Filed Oct. 9, 1969, Ser. No. 19,485

Term of patent 14 years

Int. Cl. D12—14

U.S. Cl. D14—30

FIG. 1

FIG. 2

FIG. 3

FIG. 1 is a front elevational view of a wheel as viewed from the outboard face of the wheel showing my new design.

FIG. 2 is a perspective view of the wheel of FIG. 1 also looking at the outboard face thereof.

FIG. 3 is a vertical sectional view taken on the line 3—3 of FIG. 1.

I claim:

The ornamental design for a wheel, substantially as shown.
